ABRAHAM HERSKOVITZ, OF CHICAGO, ILLINOIS.

ATTACHMENT FOR THE SWITCHES OF ELECTRIC LAMPS.

1,100,300.

Specification of Letters Patent. Patented June 16, 1914.

Application filed January 17, 1914. Serial No. 212,707.

To all whom it may concern:

Be it known that I, ABRAHAM HERSKOVITZ, a citizen of the United States, residing at Chicago, in the county of Cook and State 5 of Illinois, have invented certain new and useful Improvements in Attachments for the Switches of Electric Lamps, of which the following is a specification.

Usually the switch of an electric lamp of 10 the incandescent type is concealed within a fitting which has a socket in which the lamp bulb is secured by screw threads or some other suitable means, and the movable member of the switch has a stem which is 15 lateral relatively to the general direction of the length of the bulb and the fitting carrying it, which stem terminates on the outside of the fitting in a T-head or turn button, which is adapted to be grasped for turning 20 the stem and thereby operating the switch. In many situations this turn-button is not conveniently accessible and heretofore it has been proposed to provide an attachment in 25 the form of a lever-arm having means for removably clipping or clamping it to the turn button, and a pull-chain depending from one or each end of the lever-arm, so that when the pull-chain is drawn down the 30 switch will be operated in one direction or the other, according to which end of the lever-arm is moved downward. This lever-arm is usually radial with respect to the 35 axis of the switch-stem and in some instances extends equal distances on opposite sides thereof, and has a pull-chain (and here it may be observed that for the purposes of this application chains, cords, wires, slender rods, and other devices of a similar nature that will transmit tensile strains are 40 to be regarded as equivalents) depending from each of its ends, or the outer end of each of its arms, so that by drawing down one pull-chain the switch is moved in one direction—say to close the circuit and light 45 the lamp—and by drawing down the other pull-chain the switch is moved in the opposite direction—say to open the circuit and extinguish the light.

Thus far I have described nothing that 50 has not heretofore been done and I do not herein claim broadly anything thus far de-

scribed. But all such devices of which I am aware, as heretofore constructed, are open to objections which it is the general object of the present invention to obviate. 55 One of these objections is their narrow range of adjustability, which limits their adaptability to turn-buttons which vary in size, albeit these turn buttons of standard lamps are universally of the same general 60 T-shape.

With this objection to heretofore existing attachments of the class described in view, one specific object of the present invention is to provide such an attachment with a 65 clamp or clip which shall have a wide range of adjustability or accommodation to the end that it may be applied to T-headed turn-buttons which vary materially in size.

Another objection to attachments of the 70 class described, as heretofore constructed is, that their grasp or hold upon the turn-button is unstable and insecure, resulting in more or less play or lost motion between the lever-arm of the attachment and the turn- 75 button and with this defect in heretofore existing attachments of the class described in view, another specific object of the present invention is to provide such an attachment with means for effecting a firm connection of the lever-arm to the T-headed 80 turn-button.

Another serious objection to attachments of the class described, as heretofore constructed, is their cost of production incident 85 to details in their construction, and with this in view still another specific object of the present invention is to provide such an attachment of such simple construction that its cost of production will be low as compared with others of a like nature. 90

With these and other objects in view, the present invention consists in the features of novelty that are hereinafter described with reference to the accompanying drawing which is made a part of this specification, and in which:— 95

Figure 1 is an elevation showing one of the improved attachments in place on an electric lamp of the incandescent type. Fig. 100 2 also is an elevation of one of the improved attachments, viewed in the direction

of the arrow 2, Fig. 1. Fig. 3 is a section thereof on the line 3—3, Fig. 2, looking in the direction of the arrow. In each of the foregoing figures the turn-button and more or less of the lamp socket or fitting are shown. Fig. 4 is still another elevation of one of the improved attachments by itself viewed from still another position.

The attachment as a whole may be considered as comprising a lever-arm, A, pull-chains, B, and B', depending from opposite ends of this lever-arm or, in other words, one depending from the outer end of each of the two arms of the so-called lever-arm, and a clip or clamp which is carried at the mid-length of the lever-arm, A, and thereby defines the two arms going to make up this lever-arm. As before intimated, the so-called "pull-chains" may be chains strictly so-called or they may be cords, cables, wires, slender rods, or other things of a like nature which are adapted to transmit tensile strains to the end that when either of these so-called chains is pulled or drawn downward it will draw downward the corresponding end of the lever-arm to which it is attached. The lever-arm and its clamp are preferably formed of a single piece of torsionally and laterally elastic wire bent in a manner appropriate to giving the several parts the characteristics hereinafter described. That is to say, the wire when properly bent has loops, a and a', which form the terminals of the composite lever-arm, A, and from which the pull-chains, B and B', depend, respectively. Extending from one of these loops to the other and preferably entering into the construction of one of them—say the loop a'—the wire of which the lever-arm is made has a branch, a², which, when the attachment is in proper place on a lamp bears against what may be called the top of the T-head, D, of the turn-button and crosses it in a plane which is radial to its axis of movement as is clearly shown in Figs. 2 and 3.

Proceeding from each of the end loops, a and a', and extending toward the other of said loops, the wire has branches, a³, each of which, at about the mid-length of the composite lever-arm has a lateral deflection or bend, C, of substantially U-shape which forms one of the two jaws of the clamp or clip. Those portions of the branches, a³, which are substantially parallel with the general direction of the length of the composite lever-arm may be considered as the shanks of the jaws, C, and the wire of which the attachment is made being of elastic or spring metal, these shanks will be elastic laterally and also torsionally. The opposite sides, c', of each of the jaws may be spread apart to accommodate turn-button heads of

different widths and will clamp the opposite sides of the T-head of the turn button. 65 Their lateral elasticity tends to draw what may be called the crown, c', of each of the jaws into close contact with the under side of the T-head of the turn-button, their reaction being transmitted to the so-called top 70 of the T-head through the medium of the branch, a², the ends of which are normally held against lateral movement relatively to the branches, a³, by the end portions of the wire of which the composite lever-arm is 75 made, which end portions are wrapped around the several approximately parallel branches of the wire as shown at a⁴.

It will thus be seen that the composite lever-arm is made up of three parallel, or 80 substantially parallel branches of a bent wire, one of which branches is radial with relation to the axis of motion of the turn-button and the other two of which branches are bent to form, respectively, the two jaws 85 of a clip or clamp which is adapted to engage the T-head of a turn-button, and the opposite sides of which jaws are elastic, to the end that they will accommodate themselves to the T-heads of turn-buttons of different widths, the branches of which the jaws are formed being laterally elastic relatively to the branches first aforesaid to the end that the crowns of the jaws shall be drawn firmly against the under side of the 90 T-head of the turn-button.

What I claim as new and desire to secure by Letters Patent is:—

1. An attachment of the class described having in combination a spring clip having 100 two jaws, each of said jaws having a shank, each jaw and its shank being formed of a piece of laterally and torsionally elastic wire having at an intermediate point, a lateral deflection or bend of substantially U-shape, 105 the sides of which are elastic and have a normal tendency to contract or approach each other, and thereby clamp the head of a turn button between them and said shanks being disposed substantially parallel with 110 each other, and means for holding them against bodily lateral movement relatively to each other whereby the jaws are yieldingly forced toward each other to clamp the head of the turn button between them. 115

2. An attachment of the class described made of a single piece of elastic wire bent to form three substantially parallel branches, the terminals of the wire being wrapped around so as to unite the several 120 branches and hold them against bodily lateral movement relatively to each other, two of said branches being bent to form the jaws of a clip adapted to engage the head of a turn-button. 125

3. An attachment of the class described

having a lever-arm comprising three substantially parallel laterally elastic branches, clipping or clamping jaws carried by two of said branches and adapted to engage the 5 under sides of the T-head of the turn-button while the third branch is adapted to bear upon the top of said T-head, and means

for securing the said branches together and preventing their bodily lateral movement relatively to each other.

ABRAHAM HERSKOVITZ.
